SHIPPING CONTAINER

Leonardus Arnoldus Nicolaas Bijvoet, Overveen, and Heinrich Johann Steen, Delft, Netherlands, assignors to Inland Steel Company, Chicago, Ill., a corporation of Delaware

Filed July 10, 1963, Ser. No. 75,727

Term of patent 14 years

(Cl. D58—3)

FIGURE 1 is a side elevational view of a shipping container embodying our new design.

FIGURE 2 is a fragmentary vertical section on an enlarged scale of the shipping container shown in FIG. 1.

FIGURE 3 is a top plan view on a reduced scale and in dotted line form showing the outline of the shipping container shown in FIGURE 1.

The design for the shipping container is characterized by the provision of a side wall having a repeating pattern of alternate beads having concave cross-sections and furrows wherein the axial extent of each bead exceeds the axial extent of each furrow.

The essential feature of our design resides in the portions of the drawing shown in full lines.

We claim:

The ornamental design for a shipping container, substantially as shown and described.
